a corporation of Connecticut

Application August 1, 1940, Serial No. 349,316

2 Claims. (Cl. 235—144)

This invention relates to registering or recording mechanisms of the sort having a counter provided with a plurality of denominational order wheels and means for resetting the same.

The aim of the invention is to provide an improved, simplified, and inexpensive resetting means which is reliable and accurate and which is so constructed and arranged that upon a resetting operation all of the wheels will be picked up and turned or returned to correct zero position.

Other objects will be in part obvious and in part pointed out more in detail hereinafter.

The invention accordingly consists in the features of construction, combination of elements, and arrangement of parts which will be exemplified in the construction hereinafter set forth and the scope of the application of which will be indicated in the appended claims.

In the accompanying drawings:

Figure 1 is an end elevational view of so much of a recording or registering mechanism as is necessary to disclose the novel features of the present invention;

Fig. 2 is a horizontal sectional view taken generally on line 2—2 of Fig. 1;

Fig. 3 is a side view of one of the counter wheels with portions broken away;

Fig. 4 is a view taken centrally through the counter wheel;

Fig. 5 is a side view of one of the clutch units with portions broken away;

Fig. 6 is a sectional view through one of the clutch units; a portion of an adjacent unit and a transfer pinion being shown in broken lines;

Fig. 7 is a detail view of the mechanism for rotating the reset shaft;

Fig. 8 is a sectional view through the mechanism for rotating the reset shaft, the same being taken substantially on line 8—8 of Fig. 1; and

Fig. 9 is a diagrammatic view of the cams for moving the reset shaft in an endwise direction.

Referring to the drawings in detail, 10 designates a frame or support which may be of any suitable sort, it here being shown, more or less diagrammatically, as comprising two spaced frame plates. Supported by the frame plates for rotary movement and for limited endwise movement is a reset shaft 11 on which is mounted a plurality of counter wheels 12 operatively connected together so that upon a complete rotation of a wheel of a lower order a wheel of next higher order is advanced one step. Each wheel has on its periphery numerals running from zero

to nine. The reset shaft 11 is normally urged endwise into the inoperative position shown in Figs. 2, 4, and 8 by a spring 13 interposed between one of the frame members 10 and a collar 14 on the reset shaft. The reset shaft has a longitudinally extending groove 15 adapted, when the reset shaft is rotated counterclockwise (Figs. 1 and 3), to pick up the usual reset pawls 16 pivotedly carried by the counter wheels 12. These pawls are normally urged against the reset shaft by springs 17.

In order that the counter wheels may be turned during the registering operation in a direction opposite to that in which they are rotated during resetting, without interference by the reset shaft, the reset shaft is provided with spaced circumferential grooves 18 which, when the reset shaft is in the inoperative position shown in Fig. 4, accommodate the reset pawls. The faces 19 between the normal or larger periphery of the reset shaft and the bottoms of the grooves 18 are conical so as to form cams which will engage the reset pawls and cause them to ride out of the grooves 18 and onto the larger periphery of the shaft when the latter is moved axially to the right, reference being had to Fig. 4.

Parallel to and located at the side of the reset shaft is a rod 20 upon which is journalled a plurality of clutch units 21 respectively geared to the counter wheels. Between the successive clutch units are the usual transfer pinions 22 rotatably mounted on a rod 23. Each clutch unit includes two rotary assemblies. One assembly comprises the usual driven or so-called twenty-toothed gear 25 and a ratchet wheel 26. The other assembly comprises the usual locking disk 27, a mutilated driving gear or two-toothed segment 28, and a pivoted pawl 29 cooperating with the teeth of the ratchet wheel 26. This latter assembly further has a gear 30 meshing with a gear 31 carried by the associated counter wheel 12. The pawls 29 are urged into engagement with the ratchet wheel 26 by springs 29'. The driven gear 25 of the first clutch unit, namely, the right-hand one, referring to Fig. 2, is connected to any suitable driving mechanism, the same being here diagrammatically shown as comprising a driving gear 32.

The transfer pinions 22 through which a carrying movement is transferred from a unit of lower order to one of higher order upon each complete revolution of a unit of lower order are of the usual construction. The same has alternate long and short teeth. All of the teeth mesh with a driven gear 25 of higher order, and only the long teeth

cooperate with the mutilated gear 28 of lower order. The long teeth also cooperate with the locking disk 27 so as to prevent rotation of the transfer pinions except when the same are rotated by the mutilated gears.

In order that each of the clutch units may be locked during a registering operation so that a proper transfer is effected between successive wheels and in order that the units may be unlocked during the resetting operation so that the wheels may be rotated to zero in a direction opposite to that in which they are rotated during a registering operation, each unit is provided with a locking pawl 35 which is moved into and out of locking position with respect to the pawl 29 by moving the rod 20 axially a limited amount. Referring to Figs. 5 and 6, it will be noted that the locking pawl 35 is pivoted as at 36 to the assembly which includes the locking disk 27 and the mutilated gear 28. This pawl 35 is normally urged into the locking position shown in Fig. 5 by a spring 31. The rod 20, which, as previously stated, has a limited axial movement, is provided with grooves 40 which are adapted to respectively register with and receive the locking pawls 35 when the parts are in the normal position during which a registering operation may be effected. The right-hand walls or faces 41 of these grooves are beveled so as to provide cams which will cause the locking pawls 35 to be cammed outwardly to non-locking positions when the rod 20 is moved to the left (Fig. 6) preliminary to resetting the counter wheels. The rod 20 is moved in one direction while the shaft 11 is moving in the other direction through a lever 45 which is pivoted to a frame member 10 as at 46. The upper end of this lever has a pin 47 engaging in a groove 48 in the left-hand end of the shaft 11. The lower end of the lever has an elongated slot 49 in which engages a pin 50 carried by the rod 20.

The reset shaft 11 and the rod 20 are shown in inoperative positions in Figs. 4 and 6. In these positions, the pawls 16 of the counter wheels register with the grooves 18 of the reset shaft, and the locking pawls 35 are in locking position, the same being engaged in the grooves 40 in the rod 20. This is the condition of the parts during a registering operation. As hereinafter described more in detail, before the shaft 11 is turned during a resetting operation, it is moved to the right so that the reset pawls may be engaged with the reset groove of the reset shaft, and the rod 20 is moved to the left so as to cam the locking levers 35 of the clutch units to non-locking position with respect to the pawls 29. Thereafter, upon rotation of the reset shaft, the reset groove picks up all of the reset pawls, thereby turning the counter wheels to zero, and, during this time, the assemblies of the clutch units which carry the pawls 29 are rotated through the gears 31 and 30 while the assemblies of the clutch units which include the ratchet wheels 26 remain stationary. After the wheels have been rotated to zero position, the shaft 11 and the rod 20 are moved back to their inoperative positions shown in Figs. 2 and 6, inclusive.

Referring now to the reset driving mechanism shown most clearly in Figs. 1, 7, and 8, the same includes a driven gear 60 fixed to the reset shaft 11 and having an arcuate cut-away portion or locking recess 61. Journalled on the reset shaft between the driven gear 60 and a collar 62 is the cam gear 63, the periphery of which is interrupted by four arcuate locking recesses 64. On the opposing faces of the gears 60 and 63 are cams 65

and 66, respectively, which are so constructed and arranged that when the gear 63 has been turned to a predetermined position the cams will engage to cause the reset shaft to move axially to operative position. These cams are diagrammatically shown in Fig. 9.

The numeral 70 designates an operating shaft which, if desired, may be employed to perform other functions than that of effecting a resetting operation. One end of this shaft is adapted to receive an operating handle or crank 71. Fixed to the operating shaft 70, as by means of a pin 72, is a reset driving and control member 73 which includes a segment gear 74 adapted to mesh with the reset driven gear 60. It also includes a gear segment 75 adapted to mesh with the teeth of the cam gear 63. The teeth of the gear segment 75 are formed on the periphery of a locking flange 76, the periphery of which is adapted to engage 20 in the arcuate recesses 64 of the cam gear 63. The reset driving and control member 73 is further provided with a locking disk 77 interposed between the gear segments 74 and 75. The locking disk has on its outer face and at its periphery 25 a slight rib 79 disposed generally oppositely to the gear segment 74. The forward end of the rib is curved inwardly as at 79' and terminates short of the rear end of the gear segment 74. The periphery of this locking disk 77 is adapted to engage in 30 the arcuate recess 61 of the driven reset gear 60. The locking recess 61 and the major portion of the periphery of the locking disk 77 are of substantially like radii. However, the locking disk 77 has a smaller portion 78 of slightly lesser radius 35 than that of the locking recess 61 in order to permit of a slight rotation of the reset shaft in a direction opposite to that in which it is rotated during a resetting operation. The purpose of this is to insure that upon the next resetting operation 40 the reset groove of the reset shaft will be in a position to pick up all of the reset pawls of the several counter wheels. In order to effect such a reverse rotation of the reset shaft when the portion 78 is engaged in the recess 61, a spring 80 is 45 provided. This spring at one end is anchored to a stud 81 carried by a frame member 10. The other end of the spring is connected to a link 82 which, in turn, is eccentrically connected to the driven gear 60 by a pin 83.

The arrangement described operates, briefly, as follows: Starting with the parts in the position shown in the drawings, it will be seen that the mechanism is in condition for a registering operation. Assuming that the registering operation has been carried out with the reset operating crank 71 remaining in the position shown in Fig. 1, and it is desired to reset the counter wheels, the reset handle or crank 71 is rotated clockwise two complete revolutions. During rotation of the handle from the position shown in Fig. 1 to that shown in Fig. 7, the resetting operation is not effected because the gears 60 and 74 are disengaged. On continued rotation, however, from the position shown in Fig. 7, the gear segment 75 will rotate the cam gear 63 one-fourth of a revolution, with the result that the cams 65 and 66 on the gears 60 and 63 cooperate to cam the gear 60 and the reset shaft 11 in a direction to bring the teeth of the gear 60 into the plane of the gear 74, and during this time the locking disk 77 engages in the arcuate recess 61 so as to prevent rotation of the driven reset gear 60. At about the time that the forward end of the segment gear 74 meshes with the driven reset gear 60, the locking disk 77 engages behind the

rear face of the gear 60 so that the spring 13 cannot move the gear back to its normal position. On further continued rotation of the reset handle, the gear 74 rotates the driven reset gear 60 and the reset shaft slightly more than 360° so as to bring the wheels to zero.

At the time that the wheels are brought to zero, the gear segment 74 leaves the gear 60, and the forward end 79' of the rib 79 engages in the recess 61 so as to bring that recess into concentricity with the locking disk 77, whereupon the recess 61 receives the locking disk and the spring 13 moves the reset shaft and the driven gear back to the position shown in Fig. 8. This occurs when the handle 71 is approximately in the dotted line position of Fig. 7. On continued rotation of the handle from the dotted line position shown in Fig. 7 to the initial full line position shown in Fig. 1, the cam gear 63 is moved one-fourth of a revolution.

It is important to note that the arrangement is such that the reset shaft is reversely turned through a given angle before the shaft is turned in a direction to reset the wheels. This is of importance to insure that the reset pawls of all of the wheels will be picked up by the reset shaft and all of the wheels are thereby returned to zero irrespective of what the positions of the wheels may be at the end of the registering operation. As stated, the radius of the reduced portion 78 of the locking disk 77 is somewhat less than the radius of the locking recess 61 of the reset driven gear 60. Therefore, when the locking disk is turned to the position shown in Fig. 7, where the recess 61 receives this reduced portion 78, there is sufficient clearance between the locking disk and gear 60 to permit the spring 80 to turn the gear 60 and the reset shaft in a reverse direction through a given angle. Then, on further rotation of the driving and control member 73, the reset shaft will be driven in a resetting direction through said given angle plus 360°. This arrangement is a very simple and effective one.

As many changes could be made in the above construction and many apparently widely different embodiments of this invention could be made without departing from the scope thereof, it is intended that all matter contained in the above

description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

10 I claim as my invention:

1. In a counter, a reset shaft having a reset groove, a plurality of denominational order elements rotatable thereon and provided with pawls adapted to cooperate with said groove when the shaft is rotated in a resetting direction, a reset driven gear fixed to said shaft and having a locking recess, a driving member having a gear segment adapted to mesh with said driven gear and a locking disk adapted to engage in said recess, said locking disk having a portion of reduced diameter engaging in said recess, and a spring for reversely moving said driven gear and reset shaft a limited amount when said reduced portion engages in said recess.
- 15 2. In a counter, an endwise movable reset shaft having an interrupted longitudinally extending reset groove, a plurality of denominational order elements rotatably mounted on said shaft and provided with pawls adapted to engage said groove when said shaft is in an endwise operative position, a driven gear fixed to said shaft and having a locking recess in its periphery, a cam gear loose on said shaft for moving said shaft longitudinally to operative position, a driving and control member having a mutilated gear adapted to cooperate with said cam gear and a gear segment adapted to cooperate with said driven gear, said member also having a locking disk the periphery of which is engageable in said recess, said disk having a portion of reduced diameter engageable in said recess so as to permit a limited reverse rotation of said driven gear and reset shaft, and a spring anchored at one end and eccentrically connected to said driven gear at the other end for reversely moving said gear and reset shaft when said reduced portion is engaged in said recess.
